C. A. BROCK.

SPRING.

RECORDED IN U. S. PATENT OFFICE, MAR 12, 1917.

138005283.

Patented May 11, 1921.

UNITED STATES PATENT OFFICE.

CLARENCE A. BROCK, OF DETROIT, MICHIGAN.

SPRING.

1,380,523.

Specification of Letters Patent. Patented June 7, 1921.

Application filed February 5, 1917. Serial No. 146,605.

To all whom it may concern:

Be it known that I, CLARENCE A. BROCK, a citizen of the United States, residing at Detroit, in the county of Wayne and State 5 of Michigan, have invented a new and useful Improvement in Springs, of which the following, together with the accompanying drawings, is a specification.

The present invention relates to the construction of springs, and particularly has reference to leaf springs such as are used on automobiles and other vehicles to support the bodies thereof above the axles. The invention resides in a construction which is 10 readily applicable to the various types of springs at present in common use, such as semi-elliptic, three-quarters elliptic, full elliptic and cantaliver springs, and at the same time presents numerous advantages, as 15 regards cheapness and ease of manufacture, over the leaf springs now in ordinary use. It is to be understood that, for the purpose of simplifying the description, I have shown my invention only in its application 20 to semi-elliptic and cantaliver springs; however, it is obvious that the principle underlying my improvement is applicable to all 25 types of leaf springs now in ordinary use.

In the manufacture of the ordinary type 30 of leaf spring, as for instance a semi-elliptic automobile spring, a plurality of plates, each shorter than the preceding plate, are assembled upon a main or back plate, the latter usually providing an eye at each end 35 for attachment to the shackles. This back plate is usually thicker than the other plates, because it must take endwise and sidewise shock, and oftentimes the plates are graded in thickness throughout, becoming thinner 40 as they become shorter. Since the thicker plate or plates cannot be bent as sharply under load as the thinner ones, the ends only of all the plates are given bearing on the surface of the adjacent longer plate, that is, 45 the plates of different lengths are formed with different initial curvatures, so that these plates, when superposed one on the other but before being clamped together, are spaced apart at their central portions. 50 When bolted together to form a spring, the shorter plates are therefore straightened out and are put under an initial strain. On the other hand, the back plate is strained negatively, that is, so that some load has to be 55 applied to the spring before the back is

straightened out to its no-load, unclamped, free state. Therefore, the highly strained shorter plates will break first under undue load; the back, however, is "safe."

The springs made as above described must 60 either have a center bolt, or else nibs must be punched therein at the center to prevent slipping. Clips must be provided to prevent lifting of the ends of the shorter leaves on rebound of the spring. To prevent side 65 movement, some expedient, such as forming lips on the sides of a leaf to embrace the edges of the adjacent leaf, must be resorted to. The necessity for the above operations, in addition to the necessity for forming each 70 plate separately with a different curvature from every other plate, makes the manufacture of springs of this type exceedingly expensive and tedious; since the plates must be tempered, they necessarily become somewhat warped and invariably, when fitted together, they must be peened and hammered into place. This operation always impairs the fatigue-resistance of the spring. Obviously, if all the plates could be made over 75 each other, of the same curvature, the difficulties of manufacture and the expense of many of the above operations could be largely avoided.

The present invention contemplates the 80 use of plates or leaves which can be laid one over the other, each running the full length of the spring. Essentially it consists of a spring whose plates or leaves are made the maximum width at the center, and tapering 85 toward their ends, as hereinafter fully described, reference being had in this connection to the accompanying drawings, in which—

Figure 1 is a top plan view of a spring 90 embodying the principles of my invention.

Fig. 2 is a side view of the spring, showing the same in the position which it assumes under load.

Fig. 3 is a cross sectional view, showing 100 one form of shackle.

Figs. 4 and 5 are views illustrating the same form of shackle, parts being broken away to disclose the construction.

Fig. 6 is a view in side elevation showing 105 a specific application of my invention to the cantaliver type of spring, and

Fig. 7 is a fragmentary sectional view disclosing a modification in the manner of attaching the spring leaves to the shackles. 110

Similar reference characters refer to similar parts in the different figures.

Referring particularly to Figs. 1 and 2, 1, 1 indicate the plates, the same being of maximum width midway of their lengths, and tapering toward their ends, as shown. The spring is shown in Fig. 2 under load; obviously, in its no-load position the plates 1 assume their natural curvature which is 10 imparted to them in the forming operation. The plates 1, 1 being of the same length, and all having the same curvature, they can be formed one upon the other, simply by thinning them slightly toward their ends, 15 as shown; when thus thinned, the under surface of one plate has the same curvature as the top surface of the plate directly beneath it.

In the form shown in Figs. 3, 4 and 5, 20 each plate has a spherical enlargement 2 at each end, which may be forged, welded or otherwise formed thereon. These enlargements are adapted to seat in correspondingly shaped recesses of the shackles 3, 3, 25 and because of the bearing space required by each enlargement, it becomes desirable to dispose them in staggered relation within the shackle in order to bring the leaves or plates 1, 1 sufficiently close together. To 30 this end each alternate leaf is disposed with its longitudinal axis at an angle with the axes of the other leaves, as clearly shown in Fig. 1; all of these axes intersecting at the center of the spring. To accommodate the 35 spherical enlargements 2, each shackle 3 is preferably made in sections. A central section 4 provides hemispherical recesses on each side in staggered relation, and preferably has lubricant passageways 5, 5, communicating with said recesses. Outer sections 6, 6 are provided with hemispherical recesses which match up with the recesses of the section 4 on each side to provide bearings for the ends 2 of the spring plates, as 40 shown, the parts being assembled in place and afterward the sections 4, 4 and 6, 6 being fastened together by bolts 7, 7 at their ends, to form the shackle. The inner face of the shackle thus formed is suitably recessed as at 8, 8 to permit of free and unobstructed movement of the spring leaves on the bearings provided by their ends.

With the ends of the leaves 1, 1 thus secured for the necessary movement in the 55 shackle or shackles, it will be seen that a semi-elliptic spring is thereby formed, which may have, at its center, the usual seat 9 through which all of the leaves pass, the leaves at this point being separated, if desired, by fillers 9'. The length of seating surface is very much reduced, in comparison to springs of ordinary construction, where long seats render a considerable length of the spring ineffective. A spring of the form 60 shown in Figs. 1 and 2 does not need a long

seat, since the central section thereof, where the seating is disposed, is not weakened by the presence of any center bolt such as is used in the ordinary type of leaf spring.

According to the invention as herein disclosed, the spring is made up of one or more leaves or plates, the cross section of each leaf or plate varying along the whole length thereof in such a manner that the strength at any given section is approximately in 70 proportion to the load stress on the spring at such section. In this manner the strength of the whole spring is distributed evenly throughout its length with respect to the load which it is to sustain.

Obviously, a spring having the foregoing characteristics and made with leaves or plates 1, 1, all of the same length but of varying cross section, may be embodied not only in the semi-elliptic form herein shown 85 by way of illustration, but also in all the other forms of leaf springs now in common use, such as quarter-elliptic, three-quarters elliptic, full elliptic, cantaliver and plat-form. The disposition of the leaves or 90 plates in such form and the arrangement of parts, such as shackles, seats and the like, to accomplish these results, is merely a matter of adapting the known expedients in the spring making art to the novel form and 95 assemblage of leaves herein described. The invention is susceptible, obviously, to various changes in the arrangement of leaves and in the manner of attaching the same to the shackles, it being clear that many modifications with respect to these features will suggest themselves to those skilled in the 100 art. For example, as shown in Fig. 7, the staggered arrangement of the ends of the leaves may be dispensed with, and, if desired, the shackle 10 may be recessed at 11 to receive a row of cylindrical lugs 12, either 105 attached to or formed integral with the ends of the leaves. If desired, the recesses 11 may be in the form of elongated slots, 110 to receive the lugs 12 with freedom for the latter's movement therein, thus compensat-ing for any inequality in the lengths of the leaves. After assembling, the spaces around the lugs within the recesses may be filled up 115 with a bearing metal 11'.

Springs made in accordance with my invention have an important advantage in manufacture, in that all the leaves or plates are duplicates, both in size and in curvature. Furthermore, the necessity for sawing the leaves and for the usually practised expedients of beading, lipping, clipping and ribbing, is wholly eliminated, since each plate is independently attached to its 120 shackle, and need not be attached to any other plate. In this connection, it will be clear that the nibs, dowels, corrugations and center bolts ordinarily employed on leaf 125 springs are wholly dispensed with by my 130

improvements. It will be obvious also that the end thrust or shock on the spring, instead of being carried by a single leaf, is distributed between all the leaves. Moreover, in assembling the spring, it is not necessary that special provision be made for giving "bearing" of one leaf on another, since all the plates are the same, and are subject to the same reaction under load. In 10 manufacturing, each plate can be tested by itself and, in assembling, no peening, hammering or other fitting is necessary after heat treatment, such peening as is required by ordinary leaf springs being detrimental 15 to the fatigue-resistance of the spring.

As shown in Fig. 6, a spring constituted by leaves of the conformation and arrangement hereinbefore described, lends itself readily to adaptation as a cantaliver spring, 20 capable not only of supporting the body of the vehicle above the axle, but also of transmitting the impelling force of said axle to said body. Such a spring may be conveniently split or divided into two parts 25 13 and 14, having a common point of attachment to the frame of the vehicle at the shackle 15, the leaves being held in said shackle in any suitable manner. The part 13 may be shackled or otherwise attached above 30 the axle 16 to any member rigid therewith, such as the drum 17 used in connection with the brakes of the motor vehicle, while the part 14 may be similarly attached below the axle 16.

35 I claim,

1. A spring consisting of a series of superimposed leaves of equal length, with each leaf reduced in width from the center toward each end, with the ends of the leaves 40 in different vertical planes, and a shackle uniting the ends of the leaves and permitting a rocking movement of the end of each leaf in said shackle.

2. A spring comprising a series of superimposed leaves of equal length, with each leaf reduced in width from the center toward each end, with the ends of the leaves in different vertical planes, a shackle to which the corresponding ends of all of said 45 leaves are pivotally attached in staggered arrangement to bring the ends of alternate leaves in the same row, and with the longi-

tudinal axes of all the leaves in the same vertical plane at the center of the spring.

3. A spring comprising a plurality of 55 superposed leaves of equal lengths, and a shackle to which the corresponding ends of all of said leaves are pivotally attached, the points of attachment of the leaves being staggered in arrangement to bring the ends 60 of alternate leaves in the same row.

4. A spring comprising a plurality of leaves of equal lengths, and means for shackling the corresponding ends of said leaves, comprising bearing lugs on the ends 65 of said leaves, and a shackle providing staggered recesses for the reception of said bearing lugs.

5. A spring comprising a series of leaves of equal length provided at their ends with 70 spherical lugs, a shackle uniting the ends of said leaves composed of plates placed side by side and having recesses embracing said lugs.

6. A spring comprising a series of leaves 75 of equal length provided at their ends with spherical lugs, shackles uniting the ends of said springs composed of plates placed side by side, with their contacting sides provided with recesses embracing said lugs, and a 80 single lubricating channel communicating with each of said recesses.

7. A spring comprising a series of leaves of equal length having enlarged lugs at their ends, a shackle uniting the ends of said leaves consisting of a horizontal central plate and two outer plates united at their ends, recesses in the opposing surfaces of said plates to receive said enlarged lugs, with the recesses above said central plate in 90 85 staggered relation to the recesses below said central plate.

8. A spring comprising a series of leaves of equal length placed one above the other, with the longitudinal axes of alternate leaves 95 placed at an angle to the longitudinal axes of the remaining leaves, and with the axes of all the leaves intersecting at the center of the spring.
